UNITED STATES PATENT OFFICE.

PETER H. SIMS, OF TORONTO, CANADA.

RECORD-BOOK.

No. 806,200.

Specification of Letters Patent.

Patented Dec. 5, 1905.

Application filed January 30, 1905. Serial No. 243,258.

To all whom it may concern:—

Be it known that I, PETER H. SIMS, of the city of Toronto, in the county of York, Province of Ontario, Canada, have invented certain new and useful Improvements in Record-Books, of which the following is a specification:

The object of my invention is to devise a perpetual pocket or desk record especially adapted for the entry of due dates; and it consists, essentially, of a case adapted to receive a series of index-cards and record-cards, the case being provided with a folding cover, substantially as hereinafter more specifically described and then definitely claimed.

15 Figure 1 is a perspective view of my record-book closed. Fig. 2 is a similar view of the same opened up to expose the contents. Fig. 3 is a perspective view of one of the record-cards.

20 In the drawings like letters of reference indicate corresponding parts in the different figures.

The book comprises, as will be seen, a case A, having a receptacle B formed thereon, and 25 provided with a folding cover C. The case is preferably provided with a clasp D, such as commonly employed for purses, whereby the cover may be locked in the closed position.

30 The sides a of the receptacle are of stiff material and are provided with expandable connections with the front and back walls of the receptacle, so as to allow the receptacle to expand somewhat at the top to permit an easy inspection of its contents, and at the same time the sides are squarely and firmly attached to the bottom of the receptacle for the purpose of holding the cards at all times uniformly 35 in place and so that the cards at each end of the case shall present the appearance of the square ends of a book. The receptacle is also, it will be seen, somewhat shallow, which, with the expandable connections of the sides, permits the ready examination of the contents. In this receptacle are placed a series E of index-cards bearing the names of the months from 40 January to December. In front of these are preferably placed a series of index-cards F,

inscribed with the names of days of the week, in the present case from Monday till Saturday. Behind the index-cards sufficient room 50 is provided for a number of blank record-cards G. On these cards are made entries of any engagements, obligations, or dates for the receipt and payment of money. A card upon which a record is made is filed behind 55 the index-card for the month of maturity, so that upon a review of the filed cards at any time the user is reminded of due dates. The daily index-cards may be used to keep track of the due dates of any particular week, either 60 by special entries or by cards removed from their position under one of the monthly headings.

The case is of a convenient size for carrying in the pocket, or it may be used, if desired, for a desk-index and will be found much more convenient in every way than the ordinary memorandum-book. It is, too, a perpetual record, as the only parts requiring renewal are the blank record-cards, the index-cards being useful until worn out.

What I claim as my invention is—

1. A record-book comprising a case provided with a shallow receptacle having expanding sides squarely and firmly attached to 75 the bottom and a folding cover in combination with a series of index-cards inserted in said receptacle, substantially as described.

2. A case for a card-index record-book provided with a shallow receptacle having expanding sides squarely and firmly attached to the bottom of the receptacle; and a folding cover, substantially as described.

3. A case for a card-index record-book provided with a receptacle having stiff ends 85 squarely and firmly attached to the bottom and having expandable connections with the front and back walls, substantially as described.

Toronto, January 25, 1905.

PETER H. SIMS.
